WINDOW CONSTRUCTION

Harald T. Friis, Rumson, N. J.

Application February 15, 1949, Serial No. 76,441

7 Claims. (Cl. 160—27)

1

This invention relates to window structures. An object of the invention is to reduce the cost of manufacture of windows and the cost and labor involved in their installation.

Another object of the invention is to eliminate sticking or binding of a sliding sash in its guideways and at the same time preventing such a sliding sash from rattling.

An additional object of the invention is to eliminate the necessity of putting up and removing screens and of providing winter storage space for them.

In accordance with the invention the opening in the wall of a building which is to be closed by a window is provided around its periphery with an outwardly extending weather strip. A unitary window frame assemblage which may be constructed in a factory includes a sill, guideways for a sliding sash, housings for sash balance weights, a rotary support for a flexible member connecting the sliding sash to the weight, and a recess or chamber into which the sash may slide in the "open" position of the window. In contradistinction to the general practice of building the frame into the window opening, the frame in this invention is mounted on the outside of the wall adjacent the window opening. One end of the frame is hinged to the outside wall and the other is connected to a clamp which may draw the window into a position tightly against the outwardly extending weather strip.

The clamp is releasable from the inside of the building to permit the frame to swing slightly about its hinge to carry the sliding sash out of contact with the outwardly extending weather strips so that the sash may be slidably moved to a new position. Thereupon the clamp may be operated to lock the sash in the new position.

The invention may best be understood by reference to the following detailed description taken in connection with the accompanying drawing in which:

Fig. 1 is an elevation partly in section of the outside of a window assemblage constructed in accordance with the invention;

Fig. 2 is a horizontal section along the plane indicated by line 2—2 of Fig. 1 and viewed in the direction of the arrows;

Fig. 3 is a vertical section along the line 3—3 of Fig. 1 showing the window assemblage positioned against the outside wall of the building;

Fig. 4 is a vertical section similar to that of Fig. 3 except that the window is shown in its released or unlocked position;

2

Fig. 5 is a vertical section along the line 5—5 of Fig. 1 except that the window is swung to a much greater degree to permit inspection, cleaning or repair;

Fig. 6 is an elevation of a metal frame sash which constitutes the sliding element in a window according to this invention;

Fig. 7 is a vertical section in the plane of the line 7—7 of the structure shown in Fig. 6; and

Fig. 8 is a horizontal section of the sash of Fig. 6 in the plane along the line 8—8.

Referring to Figs. 1 and 2, one embodiment of a window frame assemblage in accordance with the invention comprises two vertical U-shaped sash weight housings 10 connected at their upper ends by a horizontal roller and screen housing 11 in which roller 12 is enclosed and at their lower ends by a second horizontal housing 13 into which the sash 14 (shown in Fig. 3 in half open position) may slide. The roller 12 is supported at each end by bearings 15 and is connected by flexible sash cords or straps 16 to the counterweights 17 which serve to balance the weight of the sliding structure including sash 14. The unitary rectangular frame structure comprising vertical members 10 and horizontal members 11 and 13 is mounted by hinges 18 at its lower end on the outside of the wall 19 adjacent a window opening so that the sash 14 in its normal closed position will overlie the entire window opening. Outer window stops 20 are attached to the frame members 10, 11 and 13 and serve as outer guides for the sliding sash 14. The lower outer stop for purposes of weatherproofing and of appearance is fashioned in the shape of a window sill.

Extending around the periphery of the window opening and attached to the wall 19 are inner stops 21 which like the outer stops 20 preferably are provided with weatherproofing material, such as felt or rubber, on their surfaces adjacent the sash 14. By means of a clamping strap 22, illustrated and described more fully in connection with succeeding figures, the window frame may be drawn inwardly swinging about its hinges 18 to press the four marginal areas of the sash 14 into close engagement with the inner stops 21 to constitute a weatherproof seal. To prevent rain entering the sash weight housings at their vertical outside abutment with the wall two vertical strips 23 are attached to the outside of the wall 19 closely adjacent the outer margins of the sash weight housings.

In Fig. 3 the wall 19 is shown with a projecting roof portion 24 which provides weather pro-

tection for the upper portion of the unitary frame. In the case of window openings considerably lower than the roof the roller housing may have an upper water-tight cap member or a strip or canopy may be attached to the outer surface of the wall 19 just above the housing 11. Metallic clamping strip 22 is connected to the hinged frame by a screw or other fastening 25 and extends inwardly beyond the housing 11 where it is provided with a hole in which is seated the end of a clamping bolt 26 having an offset portion 27 mounted on a panel 28. This panel is attached to the wall 19 beneath the upper margin of the window opening and on the lower edge of the panel the upper inner stop 21 is mounted. Turning the knob 29 to the position shown in Fig. 3 causes the clamping bolt 26 to operate as an eccentric to draw the frame inwardly and lock it in that position. The frame may be released by rotation of the bolt 26 as shown in Fig. 4 sufficiently to free the sash 14 from the stops and permit sliding it to any desired position whereupon the window again may be clamped to hold the sash tightly in the new position against rattling or entrance of rain or wind. Should it be desired to swing the window frame farther out from the building to permit inspection, cleaning, or repair the bolt 26 may be drawn vertically downward to disengage it from clamping strap 22 and the window frame may then swing outwardly as shown in Fig. 5 to a limiting position determined by metallic holders 30 connected to the housing 11 by a screw or other fastener. The holders 30 slide through holes in panel 28 and as shown in Fig. 5 they consist of two pieces that are hinged together by a bolt. In the released position of the frame shown in Fig. 4 holders 30, not shown in Fig. 4, are folded against panel 28 and serve as "stops" for housing 11. This insures that in this position of the frame the sash is free at both sides from engagement with the inner weather strips 21.

The sash 14 is connected by a flexible member 31 to the roller 12. In accordance with the invention the flexible member 31 takes the form of a screen which serves to hold the sides of the sash 14 at all times in a vertical position and which when the window sash has slid down into the lower housing 13 serves to cover the window opening and to exclude flying leaves and insects.

The sash is shown in two alternate forms. Figs. 3, 4 and 5 illustrate a frameless sash comprising solely a pane of glass or other translucent material. Figs. 6 and 7 illustrate a sash having a metal frame with a translucent pane mounted therein. It will be noted, however, that both of these sashes are specially designed in accordance with the requirements of this invention and have the common feature of a sash structure presenting a thickness that is substantially no thicker than the thickness of the translucent pane in the principal portion of the sash between its upper and lower margins. This enables the sash structure to be clamped tightly between the inner and oppositely placed outer stops of the window thus insuring a weather tight seal. It also insures that the window structures may slide into their respective housings through slots of uniform width throughout without making the slots wider than is necessary for easy action.

In the species of Figs. 3, 4 and 5 the sash 14

comprising the translucent pane is attached to the supporting screen by means of thin tapes of cotton or other suitable fabric that are sewed to the screen and glued to the translucent panel with a waterproof adhesive. This expedient will be obvious and is illustrated diagrammatically in Figs. 3, 4 and 5. Improved weather protection may be had by using well known commercial structures in which two panes of glass separated by a space are joined at their margins. A bar 32 preferably of translucent plastic material is glued or cemented to the pane throughout the central portion and near the upper margin as shown in Fig. 1 on the inside of the pane. It serves both to support the upper edge of the pane against excessive displacement in stormy weather when the sash is partly open and also as a means for grasping the sash to open or close it.

The alternative window sash 33 of Figs. 6, 7 and 8 comprises a thin flat metallic upper horizontal rail 34 of substantially the same thickness as the translucent pane 35 which it supports. The pane 35 is carried at its lower margin by flanged central members 36 extending laterally from both sides of the lower horizontal rail of the sash frame and may be seated on a leather packing strip 37 which fits between the flanges. The upper margin of the pane 35 is seated and clamped between two wooden strips 38 held tightly by the two central metal flange portions 39 of the upper horizontal rail 34. The lower margin of the supporting screen 40 is fastened by soldering or other means to a metal strip 41 which may be fastened to the upper horizontal rail 34 of the sash by means of a few cotter pins 42. The two vertical side rails 43 of the sash have less thickness than the pane. In operation the lower flanges 36 will always be positioned below the sill or lower outer stop 20. In the "closed" position of the window the upper flanges 39 will lie just below the upper coating stops 20 and 21. At the sides the stops will engage the pane. This insures a tight weather seal when the window is closed and clamped. However, to prevent access of rain through the slots at the ends of the upper flanges 39 it may be desirable to insert in these slots rubber gaskets 44. In this form the sash 33 will require no supporting bar 32 since the upper flanges 39 will serve for its functions.

It readily will be appreciated from the foregoing explanation that the window structure of this invention does not require to be built into the wall opening or to be accurately fitted to it but that it readily may be applied to the window opening irrespective of the fact that there may be considerable deviation of the window opening from ideal dimensions. It also will be understood that installation of a window according to the invention may be made after the masonry or carpentry work has been fully completed since it is necessary only to apply the window frame to the outside of the wall and not to build it into the opening. Sliding of window sashes in close fitting guides with consequent sticking and squeaking has been wholly eliminated. Most important of all when the window is in closed position there are no opportunities for air leaks or any necessity of special weather stripping to overcome such leaks. The window sash is held firmly thus eliminating rattling. Moreover the structure is such that in rapid change of weather one may have either a closed window with vision unimpaired by a screen, or a screened opening with the ventilation area unobstructed by a window sash. No small advantage is the protection

of the screen from the weather under conditions where the screen is not in use. Moreover upkeep which ordinarily involves considerable labor for maintenance of the putty or other glazing material in the less expensive windows is very greatly reduced. The window is especially advantageous for structures in which the window opening is wide relative to the height of the opening.

What is claimed is:

1. In combination, a unitary window frame assembly retractably mounted on the exterior face of a portion of building wall in overlying relation to a window opening therein, said frame assembly including a sash guideway, a sash engaging said guideway in sliding relationship, weatherstripping on said wall portion outlining said window opening and bearing upon all of the four margins of the inner face of said sash when the sash is in its closed position and said assembly is retracted, and means for pressing said weatherstripping and said sash tightly together in any position of said sash comprising a manually operable device for clamping said retractable assembly to said wall portion at will.

2. In combination, a portion of building wall that has a window opening therein, a unitary window assembly retractably mounted on the outer face of said wall portion overlying said opening, said assembly comprising a pair of vertical sash weight housings connected at their upper ends by a horizontal roller housing and connected at their lower ends by a sash housing, a roller mounted in said horizontal housing, long flexible members connected to said roller to support sash weights in said vertical housings, a fly screen attached at its one end to said roller and to a sliding sash at its other, said housings being spaced from each other to frame a rectangular opening of substantially the size of said window opening and said sash housing being deep enough to accommodate said sash when the latter is fully lowered, stops carried by said housings and extending around said rectangular opening with their sash facing-surfaces in the same plane, stops carried by said wall portion and extending around said window opening with their sash-facing surfaces in the same plane, and clamping means to draw said assembly toward said wall portion, and to release it, at will.

3. In combination, a portion of building wall having a window opening therein, a unitary window assembly retractably mounted against the exterior face of said wall portion overlying said opening, said assembly comprising a horizontal roller housing, a roller supported in said housing, a flexible screen attached at one end to said roller and attached at its other end in supporting relation to the top of a sliding sash, a counterbalance for said sash, a sash housing, vertical housing members connecting said roller and sash housings and together with them framing a rectangular opening alined with said window opening, said sash housing being deep enough to accommodate said sash when the latter is in fully-opened position, stops attached to the margins of each said opening and positioned to contact the two opposite faces of said sash when said assembly is retracted, and mean for clamping the sash tightly between said stops after the sash has been slid to a desired position, comprising a manually operable clamp connection to draw said retract-

ably mounted assembly toward the said wall portion, and to release it, at will.

4. A combination in accordance with claim 3 in which said assembly is hinge-mounted for movement about a horizontal axis lying substantially below said window opening.

5. In combination, a portion of building wall having a window opening therein, weatherstripping attached to and extending around the margin of said opening with its outer face in a common plane lying beyond the outer face of said wall portion, a unitary window frame assemblage mounted against the outer face of said wall portion overlying said opening, said assemblage comprising an overhead roller housing, a roller supported horizontally therein, a window screen attached at its upper margin to said roller for winding thereon and at its lower margin to a vertically sliding sash, and outside stops extending around the margin of the outer face of said sash in the closed position thereof, and clamping means connected to said assemblage and said wall portion for forcing said outside stops inwardly against the sash at will.

25 6. In combination, a portion of building wall having a window opening therein, inside weatherstripping attached to and extending around the margin of said opening with its outer face in a common plane lying beyond the outer face of said wall portion, a unitary window frame assemblage retractably mounted against the outer face of said wall portion overlying said opening, said frame assemblage including an overhead horizontal roller housing, a roller supported horizontally therein, a window screen attached at its upper margin to said roller for winding thereon and at its lower margin to a sash slideable vertically within said frame assemblage to cover said opening, said assemblage carrying outside weatherstripping that extends around the margin of the outer face of said sash in the closed position thereof, and clamping means for retracting said assemblage toward said wall portion at will whereby the sash is clamped between the inside and outside weatherstrippings.

40 7. A combination in accordance with claim 6 in which said sash is of substantially uniform thickness.
